UNITED STATES PATENT OFFICE.

PHILIP M. HAAS, OF YOUNGSTOWN, OHIO.

MACHINE FOR REDUCING THE SECTION OF METAL BLANKS.

1,072,001.

Specification of Letters Patent. Patented Sept. 2, 1913.

Application filed December 21, 1912. Serial No. 737,976.

To all whom it may concern.

Be it known that I, PHILIP M. HAAS, residing at Youngstown, in the county of Mahoning and State of Ohio, a citizen of the United States, have invented or discovered certain new and useful Improvements in Machines for Reducing the Section of Metal Blanks, of which improvements the following is a specification.

10 My invention relates to machines for reducing the section of metal blanks such as rods or tubes, and has to do particularly with a machine adapted to reduce the ends of bars preliminary to their being drawn through dies so that such bars may be suitably gripped for such drawing.

The object of my invention is to provide a machine for the purpose described, which will be simple in construction, effective in 20 operation, and which will expedite and cheapen the reducing of such rods or tubes.

In the accompanying drawing, which forms part of my specification I have illustrated the preferred embodiment of my invention.

Figure 1 of these drawings is a plan view of such embodiment; Fig. 2 an elevation thereof; Fig. 3 a vertical sectional view taken on the broken line III—III, Fig. 2; 30 Fig. 4 a sectional view taken on the line IV—IV, Fig. 3; Fig. 5 a sectional view taken on the line V—V, Fig. 4; Fig. 6 a longitudinal sectional view taken on the line VI—VI, Fig. 1; Fig. 7 an end view of the 35 rotatable head; Fig. 8 a sectional view taken on the line VIII—VIII, Fig. 7; and Fig. 9 a sectional view taken on the line IX—IX, Fig. 7.

In the several figures like numerals are 40 used to designate like parts.

In the practice of my invention I provide a rotatable head, and within such head, and about the axis of rotation thereof, I mount a plurality of freely rotatable rolls the 45 axes of which are inclined to, but do not lie in a plane passing through and including, the axis of rotation of said head. Also I arrange the rolls so their peripheries are at equal distances from the axis of rotation of 50 said head, such distances being less than the radius of a blank to be reduced. When the rotatable head, having the rolls arranged therein as described, is suitably driven, a rod or other blank to be reduced will, when 55 brought to a position in front of such rolls and in line with the axis of rotation of said

head, be engaged by the rolls and dragged through and between them having its section reduced to a diameter equal to twice the distance of the rolls from the axis of rotation 60 of said head. Cooperating with said head I provide means for driving said carriage blank to be reduced and to hold it in operative position in front of said roll-provided head. Also, in order to pull the blank, borne 65 by said carriage, from engagement by said rolls and against the action thereof tending to draw the blank in the opposite direction, I provide means for driving said carriage away from said head. 70

Referring now more particularly to the embodiment of my invention shown in the drawings, I mount the head 1 upon a shaft 2, which is suitably supported in bearings 3 and 4, and is driven by a motor 5, or other 75 source of power, through gear wheels 6 and 7. Two reducing rolls 8 are shown mounted in the head 1 on opposite sides of the axis of rotation 9 thereof. In order to arrange such rolls in any desired position with relation to the axis 9, each roll 8 is mounted so as to rotate freely in an adjustable casing consisting preferably of a cylinder 10, the axes of which extend radially from the axis 9. Each roll 8 is preferably disk-shaped, 80 having a convex curved periphery, and is mounted within its casing 10 by means of a suitable pin 11. The casings 10 are held in their desired relative positions by means of a clamping frame 12 adapted to be secured to the head 1 by bolts 13, and by set screws 14 extending through the head and abutting against the outer ends of the casings. Also, in order to guide a rod entering the rolls, suitable adjustable guide plates 85 15 are secured to the head 1 by bolts 16 and are held in their desired positions by set screws 17. 90

In the operation of my machine, as thus far described, the roll casings 10 are adjusted radially with relation to the axis 9 to the end that the periphery of each roll 8 will be at a distance from the axis 9 equal to the radius of the required reduced rod. Also, the casings 10 are further adjusted angularly about their own axes so that the axes of the rolls 8 will be in a plane exclusive of the plane of the axis 9. As will be readily understood, the direction of inclination of the axes of the rolls 8 with relation to the 110 axis 9 will depend on the direction of rotation of the head 1; and the amount of such

inclination may best be varied inversely with relation to the size of the blanks to be operated upon and directly with relation to the ductility thereof. When such adjustment has been effected, a blank, suitably held against rotation and brought to position in contact with the rolls 8, will be engaged by such rolls, the head 1 being rapidly rotated, and, by being dragged between them, the blank will have its section reduced to a diameter equal to the spacing of the rolls.

Having reference now to the means for handling a blank of material to be operated upon as described, the carriage 18 is slidably mounted upon a suitable frame 19. A clamp, adjustable to receive any desired size of blank, is secured to the top of the carriage, and consists of an adjustable block 20, and a movable and adjustable block 21. The movement of the block 21 is effected, as shown, by means of a lever 22 and toggle 23. Secured to the central bottom portion of the carriage 18 is a rack 24 adapted to be engaged by a pinion 25 keyed to a shaft 26, which in turn is rotatably mounted in the frame 19. Two means are secured to the shaft 26 for rotating it in order to move the carriage, such means consisting of a hand wheel 27 and a worm wheel 28. The worm wheel 28 is driven by a suitable worm gear 29 secured to a shaft 30, which may be driven through the belt wheel 31, belt 32 and belt wheel 33, secured to the shaft 2. In order to move the worm gear 29 from operative engagement with the wheel 28, the shaft 30 is pivotally mounted in a yoke 34; and, in order to support the free end of the shaft 30 in its alternate raised and lowered positions, I mount the outer end of said shaft in a casing 35, which in turn is movably secured to a supplemental frame 36 secured to the main frame 19 by means of bolts 37. The attachment of the casing 35 to the frame 36 is preferably effected by means of bolts 38, whose heads 39 engage the inner wall of the casing 36, and which move through slots 40 therein. The casing 35, and the shaft 30 mounted therein, are held in raised position by means of a trigger 41, which is pivotally mounted in the casing 35, and which rests on a ledge 42 formed in the supplemental frame 36. The said trigger is held yieldingly in ledge-engaging position by means of a spring 43; and a trip finger 44 is secured to said trigger and lies in the path of a projecting abutment 45, adjustably secured to the movable carriage 18, the arrangement being such that, when said carriage (in moving away from the head 1) reaches a predetermined point, the abutment 45 will strike the finger 44 and thereby release the trigger 41 from its supporting ledge 42, letting the frame 35 and shaft 30 drop until the bolts 38 rest in the bottom of the slots 40. To the end that the abutment

45 may be adjusted with relation to the carriage 18, said abutment is preferably secured to a bar 46 provided with slots 47 through which bolts 48 extend into the carriage 18.

In the drawings I have shown a rod 49 clamped to the carriage 18, the end of the rod having been reduced by the action of the roll-provided head 1. In thus pointing, or reducing the end of a rod, the rod is first secured to the carriage 18 between the clamping blocks 20 and 21, such blocks having been pre-arranged to engage a rod of a known diameter and to hold such rod in line with the axis of rotation 9 or the head 1. The carriage is then advanced to a position in front of said head by turning the hand wheel 27, such movement being effected through shaft 26, pinion 25, and rack 24. When the rod is engaged by the rolls 8 in the head 1, which together with the shaft 30 is preferably rotated continuously, it will be drawn between such rolls, and the carriage will be dragged along with it. In this operation it will be understood that the shaft 30 is in lowered position, so that the worm gear 29 is not in engagement with the worm wheel 28. The desired length of the reduced section of the bar 49 being predetermined, an abutment may be placed in the path of advance of the bar, and in this disclosure the end of the shaft 2 affords such an abutment. After the rod has been reduced the required amount the shaft 30 is raised until the worm 29 thereon engages the worm wheel 28, and in such position the rotation of the shaft 30 will (through the worm gear 29, worm wheel 28, shaft 26, pinion 25 and rack 24) be effective to move the carriage away from the head and draw the rod from the bite of the rolls 8 and against the action of said rolls to move the bar in the opposite direction. By thus withdrawing the bar, whatever irregularities may have been formed on the reduced portion thereof will be removed, or smoothed out. When the bar has been entirely withdrawn from the rolls, the abutment 45 strikes the trigger 44 and causes the trigger 41 to move from the seat 42, the result being that the rod 30 drops and the withdrawing movement of the carriage is stopped. A second rod may then be clamped to the carriage 18 and the operation repeated, as will be readily understood.

I claim herein as my invention:

1. In a machine for reducing the section of a metal blank, the combination of a rotatable head, a plurality of freely rotatable rolls mounted in said head and about the axis of rotation thereof, the axis of rotation of said head lying in a plane exclusive of the axes of rotation of said rolls, means for permitting the adjustment of the axes of rotation of said rolls radially and angularly with relation to the axis of rotation of said head, and means for driving said head.

2. In a machine for reducing the section of a metal blank, the combination of a rotatable head, a plurality of roll-carrying casings mounted in said head, a plurality of freely rotatable rolls mounted in said casings and arranged about the axis of rotation of said head, said roll casings being mounted for two adjustments, whereby said rolls may be adjusted radially and angularly with relation to the axis of rotation of said head, and means for driving said head.
3. In a machine for reducing the section of a metal blank, the combination of a rotatable head, a plurality of cylindrical roll-carrying casings mounted in said head and having their axes radially arranged with relation to the axis of rotation of said head, said casings being adjustable radially with relation to said axis and angularly about their own axes, a freely rotatable roll mounted in each of said casings, and means for driving said head.
4. In a machine for reducing the section of a metal blank, the combination of a rotatable head, a plurality of freely rotatable rolls mounted in said head and about the axis of rotation thereof, a movable carriage provided with means for engaging a metal blank to be reduced by said head, means for advancing said carriage toward said head, separate means for withdrawing said carriage, and means for driving said head.
5. In a machine for reducing the section of a metal blank, the combination of a rotatable head, a plurality of freely rotatable rolls mounted in said head and about the axis of rotation thereof, a movable carriage provided with means for engaging a metal blank to be operated upon by said head, means for moving said carriage and a blank borne thereby away from said head, said carriage-moving means being adapted to be rendered ineffective after the blank borne by said carriage has been withdrawn from the bite of said rolls.
6. In a machine for reducing the section of a metal blank, the combination of a rotatable head, a plurality of freely rotatable rolls mounted in said head and about the axis of rotation thereof, a blank-sustaining carriage movable to and from said head, means for driving said carriage, and a rotatable driving shaft movable to and from engagement with said carriage-driving means.
7. In a machine for reducing the section of metal blanks, the combination of a rotatable head, a plurality of freely rotatable rolls mounted in said head, a blank-sustaining carriage movable to and from said head, carriage-driving mechanism including a movably-mounted rotatable shaft, means for holding said shaft in carriage driving position, and means for rendering said holding means ineffective when said carriage reaches a predetermined point.

In testimony whereof I have hereunto set my hand.

PHILIP M. HAAS.
